FIG. 5

Winfield Dexter Smith, Inventor

By his Attorney

W. B. Hutchinson.

UNITED STATES PATENT OFFICE.

WINFIELD DEXTER SMITH, OF NEWARK, NEW JERSEY, ASSIGNOR OF ONE-HALF TO
BENJAMIN MEYER, OF NEWARK, NEW JERSEY.

PIVOT-CLEAT.

1,304,616.

Specification of Letters Patent. Patented May 27, 1919.

Application filed March 5, 1918. Serial No. 220,480.

To all whom it may concern:

Be it known that I, WINFIELD DEXTER SMITH, a citizen of the United States, and a resident of the city of Newark, county of Essex, and State of New Jersey, have invented a new and useful Improvement in 5 Pivot-Cleats, of which the following is a full, clear, and exact description.

My invention relates to improvements in 10 cleats for boots and shoes, and especially to a device of this character which is adapted for use on golf shoes, though it can be used for other purposes. In playing golf it is necessary in order to play successfully to 15 have shoes that will not slip on the turf or dirt, and it is customary to have the boot or shoe soles provided with cleats or hobs for this purpose. Such fixed devices prevent slipping, but there are disadvantages 20 in their use. In making a stroke, for instance, especially if the stroke is one in which considerable energy is used, the body is twisted somewhat and the driver has a slight pivotal movement first on one foot 25 and then on the other. With the fixed cleats or hobs this action is somewhat interfered with and sometimes where successive shots are made in this way, the twisting strain being interrupted by the fixed cleats or hobs 30 will cause a lameness or strain in the foot, ankle or leg. The object of my invention is to produce a simple device which can be applied to the sole of a boot or shoe, and which while preventing the foot from slipping 35 bodily, will permit an easy turning movement on either foot for the wearer and enable him to pull off a better shot than he would otherwise. Moreover, the device which embodies my invention has a tendency 40 by reason of its freedom of movement to prevent the wearer from tearing up the turf, especially on the putting green.

In consonance with this idea, my invention comprises a pivot cleat embodying two 45 members, one of which is adapted for attachment to the sole of a boot or shoe, and the other member of which has a pivotal connection with the first member and is adapted for contact with the ground, the 50 second member being roughened or constructed so that it will not slip on the ground. By this arrangement it will be seen that the lower member anchors itself to the ground, while the foot and the upper member can turn but can not slip bodily in any 55

direction. All of which will be more clearly understood from the description which follows.

Reference is to be had to the accompanying drawings forming a part of this specification, in which similar reference characters indicate corresponding parts in all the views.

Figure 1 is an inverted plan of my improved device as applied to the sole of a 65 boot or shoe.

Fig. 2 is an enlarged detail inverted plan of the device.

Fig. 3 is an inverted plan of the upper member with the fastening clips spread out. 70

Fig. 4 is a plan view of the lower member, and

Fig. 5 is a cross section on the line 5—5 of Fig. 2.

The upper member of the device consists 75 of an essentially flat plate 10 which is preferably provided with one-half 11 of an annular ball race, and with outwardly extending ears 12 which are perforated as shown at 13 in order that screws or other fastening 80 devices may be passed through the holes to fasten the plate to the sole. The lower member 14 is likewise a generally flat plate having the complementary half 15 of the ball race which receives the bearing balls 16, 85 these lying as shown in the two halves 11 and 15 of the ball race. The plate 14 is also roughened in some way to prevent it from slipping on the ground, and a convenient way is to press bosses 17 which will 90 project downwardly from the plate and enter the ground or turf.

It is obvious that the plates 14 and 10 must be held in the right relation, and a simple way to accomplish this is to have the 95 upper plate 10 provided with projecting cleats 18 which can be doubled over beneath the edge of the lower plate as shown, thus preventing the lower plate from being displaced but permitting it to turn freely with relation to the top plate.

A device of the kind described is attached to the sole of each boot or shoe of a pair, and the wearer pays no attention to them in playing his game but makes his stroke precisely as he would with ordinary cleats. The result is, however, that while the foot can not slip bodily, the wearer in the natural movements of pivoting slightly or twisting slightly first on one foot and then on 110

the other, can do this with the greatest facility, and it does not in the least interfere with his stroke. On the contrary, it facilitates the easy turning and movement 5 of the body in making the stroke, and a player gets a much smoother stroke and a better "follow through" than where the ordinary devices are used.

I have shown in the drawings a preferred 10 embodiment of my invention in which the two members 10 and 14 are provided with a ball bearing so that one moves freely with reference to the other, but it will be obvious that very many departures from the particular structure shown can be made without 15 affecting the invention, the essential thing of which is to have the pivotal connection between the two plates of the cleat. Also it will be understood that while ball 20 bearings are desirable, they are not essential, and that any means of keeping the two

plates in the right relation to each other can be substituted for the means shown, and that any suitable means can be employed for fastening the device to the shoe.

25

I claim:—

1. The combination with a golf shoe or the like, of a single anti-slipping cleat pivoted on the shoe near the front part of the sole, whereby the wearer can pivot on the 30 cleat while the latter remains anchored.

2. The combination with a golf shoe or the like of a single cleat provided with downwardly projecting bosses, said cleat being pivoted on the shoe near the front part 35 of the sole, whereby the wearer can pivot on the cleat while the latter remains anchored.

WINFIELD DEXTER SMITH.
